(57) **CLAIM**

The ornamental design for a toy having movable legs, as shown and described.

DESCRIPTION

FIG. 1 is a top perspective view of a toy having movable legs according to the present invention.

FIG. 2 is a bottom perspective view of the toy having movable legs illustrated in FIG. 1.

FIG. 3 is a top plan view of the toy having movable legs illustrated in FIG. 1.

FIG. 4 is a bottom plan view of the toy having movable legs illustrated in FIG. 1.

FIG. 5 is a side elevation view of the toy having movable legs illustrated in FIG. 1.

FIG. 6 is another side elevation view of the toy having movable legs illustrated in FIG. 1.

FIG. 7 is front elevation view of the toy having movable legs illustrated in FIG. 1.

FIG. 8 is a rear elevation view of the toy having movable legs illustrated in FIG. 1.

FIG. 9 is a top perspective view of the toy having movable legs illustrated in FIG. 1 and having leg portions thereof in a folded position.

FIG. 10 is bottom perspective view of the toy having movable legs illustrated in FIG. 1 and having leg portions thereof in a folded position.

FIG. 11 is a top plan view of the toy having movable legs illustrated in FIG. 1 and having leg portions thereof in a folded position.

FIG. 12 is a bottom plan view of the toy having movable legs illustrated in FIG. 1 and having leg portions thereof in a folded position.

FIG. 13 is a side elevation view of the toy having movable legs illustrated in FIG. 1 and having leg portions thereof in a folded position.

FIG. 14 is another side elevation view of the toy having movable legs illustrated in FIG. 1 and having leg portions thereof in a folded position.

FIG. 15 is front elevation view of the toy having movable legs illustrated in FIG. 1 and having leg portions thereof in a folded position; and,

FIG. 16 is a rear elevation view of the toy having movable legs illustrated in FIG. 1 and having leg portions thereof in a folded position.
